UNITED STATES PATENT OFFICE.

FRANK M. LEAVITT, OF BROOKLYN, NEW YORK, ASSIGNOR, BY MESNE ASSIGNMENTS, TO THE BERNADIN METALLIC CORK COMPANY, OF EVANSVILLE, INDIANA.

BOTTLE-CAPPING MACHINE.

SPECIFICATION forming part of Letters Patent No. 527,209, dated October 9, 1894.

Application filed September 2, 1893. Serial No. 484,623. (No model.)

To all whom it may concern:

Be it known that I, FRANK M. LEAVITT, a citizen of the United States, residing at Brooklyn in the county of Kings and State of New York, have invented certain new and useful Improvements in Bottle-Capping Machines; and I do hereby declare the following to be a full, clear, and exact description of the invention, such as will enable others skilled in the art to which it appertains to make and use the same.

My invention relates to bottle capping machines, and more particularly to a machine for applying a metallic cap provided with a depending flange to the head of a bottle having an annular shoulder against which the flange of the cap is pressed in locking contact.

The primary object of the invention is to provide a simple, compact machine, adapted to operate automatically; power being supplied from a suitable driving shaft.

Further objects of the invention are to provide effective means for feeding or forcing the bottle upward in position to receive a cap, in combination with automatic devices for feeding and applying the caps, and pressing their flanges into locking contact with the bottle shoulders; to provide an adjustable bottle holding frame, thus adapting the machine for bottles of different size; and finally to so combine the bottle feeding mechanism, the cap feeding devices and the means for compressing the cap flange upon the bottle shoulders that the whole may be operated from a single source of power, the several steps in the operation being so related as to insure a steady and continuous automatic action of the machine.

With these ends in view the invention consists in the several features of construction and various combinations of parts hereinafter fully described and pointed out in the appended claims.

In the accompanying drawings forming a part of this specification, Figure 1 represents a side elevation of my improved machine, certain parts being shown by dotted lines. Fig. 2 is a plan view of one form of bottle holding frame adapted for use with the machine. Fig. 3 is a front elevation of the ma-

chine. Fig. 4 illustrates a modified form of bottle holder. Fig. 5 shows a vertical central section of a part of the holder shown in Fig. 4. Fig. 6 is a perspective view of the cap feeding finger. Fig. 7 is a vertical section 55 showing the cap feeding devices and the mechanism for compressing the cap flange upon the bottle shoulder. Fig. 8 is a horizontal section taken on the line VIII—VIII of Fig. 7. Fig. 9 is a plan view of the cap 60 feeding table, with the feeding finger and spring in place, and Fig. 10 is a plan view partly in section of the revolving head or chuck of the flange compressing devices.

The numeral 1 indicates the hollow standard of the machine, preferably provided with a flared base 2. The standard is formed with bearings 3 and 4, which receive a main driving shaft 5, provided at one end with a fixed belt pulley 6, an idler 7, and a gear pinion 8. 70 Upon the opposite end of the main shaft 5, is loosely mounted a sleeve 9, having an integral radially slotted wheel 10, and a bevel gear-wheel 11, the latter meshing with a similar gear-wheel 12, on the lower end of a spindle 13, supported in bearings 14, of a bracket 15, secured to the standard 1, as shown. The upper end of the spindle 13, extends through a central opening 16, in the bottle supporting table 17; said table being formed integral 80 with the bracket 15, as shown in Fig. 1. A bottle holding frame 18, is secured adjustably upon the upper end of the spindle above the table 17. Said holder consists of a spider 19, the radial arms 20, of which are curved at 85 their outer ends 21 and provided with curved spring fingers 22, adapted to embrace and hold a bottle as shown in Figs. 1 and 2. The central sleeve 23, of the holder is longitudinally grooved to receive a spline or feather 90 24, projecting from the spindle 13, and the holder is vertically adjustable upon the spindle to adapt the machine for bottles of different heights, the set screw 25, serving to retain the holder at any adjustment, and the spline 95 24, serving to prevent any rotary movement of the holder except with the spindle.

The radially slotted wheel 10 (see Figs. 1 and 3) is arranged concentric with the bevel gear-wheel 11, and the movement of said

wheel 10, as will be hereinafter explained more fully, controls the rotation of the spindle 13, and the bottle holder attached thereto. The gear pinion 8, upon the shaft 5, meshes with a gear-wheel 26, mounted upon one end of a counter shaft 27, supported in bearings 28, projecting from the standard 1. At the opposite end of said shaft is rigidly mounted a cam 29, carrying a roller 30, mounted upon a stud 31, projecting from the cam, and adapted to successively enter the slots of the wheel 10. Said cam is arranged below and in the same vertical plane with a roller 32, mounted upon a cross pin 33, at the lower end 15 of a plunger 34. This plunger is supported within a suitable tubular opening or chamber 35, formed in the bracket 15, (see Fig. 1) and consists of a rod 36 provided at its upper end with a disk 37, and at its lower end with a head 20 or yoke 38. A spring 39, surrounds the plunger within the chamber 35, and serves to normally depress the plunger which is intermittently forced upward by the contact therewith of the cam 29.

25 Within the standard 1, the shaft 27, is provided with a bevel gear-wheel 40, which meshes with a similar gear-wheel 41, mounted rigidly upon the lower end of a vertical shaft 42, (see Fig. 1) supported in suitable bearings 30 within the hollow standard. At the upper end of the standard 1, the vertical shaft 42, is formed with an annular shoulder 43, (Fig. 7) upon which is supported the revolving feed table 44, for feeding the caps to the compressing mechanism. The upper end of the standard 1, is provided with a head plate 45, upon which is supported the feeding and compressing mechanism, (the construction of which will be described) and to which is secured by 40 bolts 46, the cap plate 47.

The shaft 42 extends upwardly through the cap plate 47, and is preferably jointed at the point 48, to facilitate the removal of the parts when necessary. Below the cap plate a horizontally arranged gear-wheel 49, is mounted upon the shaft 42, said shaft having an annular shoulder 50, above which said gear-wheel is supported. A short shaft or stud 51, depends from the cap plate 47, and is formed with a flange 52, at its lower end, while its upper end is supported in a bearing 53, in the cap plate and held by a nut 54. Upon the shaft 51, is mounted a sleeve 55, having an integral gear-pinion 56, meshing 45 with the gear-wheel 49. Below the pinion 56, upon the sleeve 55, a gear-wheel 57, is supported, which meshes with gear-teeth 58, of the head or chuck 59, to revolve the latter.

The cap feeding mechanism consists of a 60 circular table 44, supported upon the shaft 42, to revolve therewith, and formed with a cam groove 60, which receives a roller 61, depending from the feed finger 62. Above the revolving table 44, is supported a stationary feed-plate 63, of the irregular or cam form shown in Fig. 8. This plate is suspended above the revolving table by bolts 64, which

pass through the cap plate and are held by nuts 65. The plate 63 has an opening 66, to allow the passage through it of the shaft 42, and is formed with diverging strengthening ribs 67 as shown, and with a raised off-set or chamber 68, within which the finger 62, slides. The space 69, between the edge of the stationary plate 63, and the periphery of 75 the revolving table 44, forms a passage for the caps, which are laid upon the table, and are caught by the end of the reciprocating finger 62, which is recessed at the point 70, (see Fig. 6) and formed with a flange 71, to 80 engage the head of the cap. A light leaf spring 72, is secured to the frame-work of the machine adjacent to the finger 62, and across the path of reciprocation to prevent the backward movement of the caps after they have 85 been carried out by the finger. It will be understood that the plate 63 serves to retain the finger in its position, and that said finger through its roller 61, is given a reciprocating movement when the table 44, is revolved. 90

I will now describe the devices for applying the cap to the bottle and compressing the cap flange about the shoulder of the bottle. Above the cap plate 74, a cam wheel 73, is mounted upon the upper end of the shaft 42, 95 and held by a nut 47. As this cam wheel revolves with the shaft, its cam surface contacts with a roller 75, mounted upon a stud 76, projecting from a rocking lever 77, fulcrumed upon a cross pin 78, of a bracket 79. The inner end of said lever is provided with a retracting spring 80, one end of which is secured to a lug 81, of the lever, while its opposite end is secured to the cap plate as clearly shown in Fig. 7. The outer end of the lever 100 77, projects into a boxing 82, through which passes a centering rod 83. This rod is suspended from the top of boxing 82, and is screw-threaded at its upper end, and held by a nut 84. It is formed at its lower end with a socket 85, to receive the cap, as shown in Fig. 7. The outer end of the lever 77, is slotted or forked to allow the rod 83, to pass through it, and said lever is recessed to form a striking head 84^x, adapted to strike the 105 flanged upper end 85^x, of a sleeve 86, which surrounds the rod 83, and is formed at its lower end with a beveled surface 87, adapted to operate a cam block of the chuck as will be described hereinafter. 110

The sleeve 86, is loosely supported within a stationary sleeve 88, screw-threaded at its upper end to the boxing 82, and extending down through a circular opening in the cap plate 47. The sleeve 88, is provided with an annular 115 collar 89, which bears against the under side of the cap plate, and is formed at its lower end with a ball enlargement 90, which serves as a bearing for the revolving head or chuck which will now be described. (See Figs. 7 and 10.) 120 The head is centrally bored to receive the centering rod 83, and the neck of the bottle and has its gear-wheel 58, bolted thereto. This gear-wheel is formed with a socket 91, to re-

ceive the ball 90, of the sleeves 88. This ball and socket connection of the parts permits the head to yield sufficiently to compensate for any unevenness or inequalities in the bottle necks.

Referring to Figs. 7 and 10, the chuck is formed with three series of radial seats or chambers, each series comprising an upper space or channel 92, a lower channel 93, and an intermediate hollow partition 94. Within the lower channel 93, is arranged a sliding block 95, recessed at its inner end to receive the crimping or compression roller 96, which is mounted upon a pin or stud 97. The outer end of the block 95, is provided with a plug 98, which serves as a striking surface to receive the impact of a rocking lever 99, which is pivotally mounted upon a fulcrum 100, supported in ears 101, projecting from the body of the chuck. Within the hollow partition 94, is seated a spiral spring 102, one end of which rests against the end wall of the partition, while the opposite end bears against a lug 103, projecting upwardly from the block 95, the function of said spring being to retract the block 95, after it has been forced inwardly by the rocking lever 94. A cam block 104, is supported within the upper channel 92, and consists of a short rod 105, formed with a cam faced head 106, and a tubular portion 107, having an outer striking surface 108. The rod 105, extends into the tubular portion 107 of the block, and a spiral spring 109, is interposed between the end of the rod and the wall of the portion 107. A stop lug 110, projects from the side of the rod into an elongated slot 111, of the tubular part of the block, to limit the movement of the rod.

The operation of the machine is as follows:—The bottle holder being supplied with bottles, and the machinery started, one of the bottles will rest upon the head 37, of the plunger and be raised by the contact of the cam 29, with the roller 32, upon the lower end of the plunger. Simultaneously the cap is fed to position by the finger 62, through the revolution of the table 44, the roller 61, of the finger traveling within the cam 64, of the table. The chuck is revolved through the gearing 49, 56, 57 and 58, and after the cap is in position upon the bottle, the crimping or compression of the flange about the bottle shoulder is effected as follows: The cam surface of the wheel 73, contacts with the roller 75, of the lever 77, thus depressing the outer end 84, of said lever, which in turn forces downward the sliding sleeve 86, the lower beveled end of which strikes against the cam surface of the block 104, forcing said block outwardly, so that it strikes the upper end of the rocking lever 99, and tilts said lever, thus throwing the lower end of the lever against the block 95, forcing said block inwardly and pressing its roller 96, against the cap flange and bottle as illustrated in Fig. 7. The reverse movement of the lever 77, releases the parts which assume their normal position

ready for the next operation. The cam 29 through its roller 30, gives a partial rotation to the slotted wheel 10, and through the gearing 11 and 12, the spindle 13, is likewise partly revolved. Thus a bottle is presented to the action of the plunger as soon as the preceding one is capped and moved away.

It will be observed that the parts are so adjusted and relatively arranged that the operation of the machine is automatic and continuous, it being only necessary to control the feed of bottles by hand.

It is obvious that the number of slots in the wheel 10, the number of bottle clamps, and the number of crimping wheels may be varied at will, provided the relative adjustment is maintained, and the required correspondence as to number is observed.

The sliding blocks of the compression devices and the ball and socket bearing of the revolving chuck insure the required yielding to compensate for irregularities in the surface or contour of the bottles.

In Figs. 4 and 5, I show a modified form of bottle holder consisting of a disk 115, formed with a series of bottle openings 116 each of which is fitted with a thimble 117; provided with a lining 118, of felt or similar material.

I reserve to myself the right to make all such minor changes or modifications in the construction of the machine as may fall within the scope of the invention as defined in the following claims.

Having thus fully described my invention, what I claim as new, and desire to secure by Letters Patent of the United States, is—

1. The combination, in a bottle capping machine, of mechanism for compressing the flange of the cap around the bottle shoulder, bottle feed-mechanism comprising a spring-pressed plunger, a bottle holder secured upon a spindle and cam mechanism arranged below the plunger for raising the bottle and imparting a partial revolution to the spindle, together with mechanism for automatically feeding the caps, substantially as described.

2. In a bottle capping machine, the combination with a supporting standard and a driving shaft, of mechanism for raising the bottle, devices for compressing the caps into engagement with the shoulder of a bottle, and a revolving table and means for automatically feeding the caps, all operated from a single source of power, substantially as described.

3. In a bottle capping machine, the combination with the standard and driving shaft, of a revolving feed table, automatic compression devices, a bottle plunger, a spindle carrying the bottle holder and a cam and roller substantially as described for imparting a partial rotation to the bottle holder and raising the bottle plunger, substantially as described.

4. In a bottle capping machine, the combination with the cap feeding and compressing

- mechanism, of a plunger, a cam for operating the plunger, a radially slotted wheel arranged to be engaged by a roller projecting from said cam, a spindle having a gear connection with said slotted wheel, and a bottle holder having radial arms corresponding in number to the slots in said radially slotted wheel, the whole being so arranged relatively that a step by step rotation is imparted to said spindle to successively present the bottles in the holder to the action of the plunger, substantially as described.
5. The combination with a standard and driving shaft, of a spindle geared to said shaft and carrying the bottle holder, a counter-shaft also geared to the driving shaft, a vertical shaft in gear with said counter-shaft, a revolving feed table mounted upon said vertical shaft and a plunger and cam mechanism for raising the bottle, substantially as described.
6. In a bottle capping machine, the combination with the driving shaft, the cap feeding and compressing mechanism, and the plunger for raising the bottles, of a cam mounted upon a counter-shaft, and arranged to operate the plunger, a radially slotted wheel mounted loosely upon the driving shaft, and a gear wheel turning with said slotted wheel, to revolve the bottle holder spindle, when the slotted wheel is turned by said cam, substantially as described.
7. The combination in a bottle capping machine, with the standard, driving shaft, and cap feeding and compressing mechanism, of a bottle holder spindle, and mechanism for operating said spindle, comprising bevel gearing, a radially slotted wheel loosely mounted on the driving shaft and a cam mounted on a counter-shaft and provided with a projecting roller adapted to enter the slots of the wheel and revolve the latter by a series of partial revolutions, substantially as described.
8. In a bottle capping machine, the combination with a stationary bottle-supporting table formed with a plunger opening and a central spindle opening, of a spindle projecting above said table, and a bottle holder adjustably secured to said spindle, substantially as described.
9. In a bottle capping machine, the combination with a stationary bottle-supporting table formed with a plunger opening and a central spindle opening, of a spindle projecting above said table and a bottle holder adjustably secured to said spindle and comprising a series of radial arms provided with clamping fingers, substantially as described.
10. In a bottle capping machine, the combination with a stationary bottle supporting table formed with a plunger opening and a central spindle opening, of a spindle projecting above said table and a bottle holder secured to said spindle to turn therewith and means for adjusting said holder vertically, substantially as described.
11. In a bottle capping machine, the combi-

nation with means for feeding the bottles and mechanism for compressing the caps, of cap feeding mechanism comprising a revolving feed table provided with a cam slot, and a reciprocating finger having a roller traveling in said slot, substantially as described.

12. In a bottle capping machine, the combination with means for feeding the bottles and mechanism for compressing the caps, of cap feeding mechanism comprising a revolving feed table formed with a cam slot, a reciprocating finger having a roller traveling in said slot and a stationary plate supported above the revolving table, substantially as described.

13. In a bottle capping machine, the combination with the revolving feed table, of a reciprocating finger, a stationary plate supported above said table, and a spring arranged across the path of movement of said finger, substantially as described.

14. In a bottle capping machine, the combination with the revolving feed table formed with a cam slot as described, of a reciprocating finger provided at one end with a depending roller adapted to enter said slot, and recessed and flanged at its outer end, substantially as described.

15. In a bottle capping machine, the combination with the main shaft, and a counter-shaft, of a vertical shaft geared to said counter-shaft, a revolving feed table mounted on said vertical shaft and formed with a cam slot, a reciprocating feed finger, and a stationary plate supported above the feed table, substantially as described.

16. In a bottle capping machine, the combination with a revolving vertical shaft extending through the cap plate of the machine, of a cap feeding table revolving with the shaft, a cam wheel mounted upon the upper end of the shaft, and a rocking lever one end of which contacts with said cam wheel, while the other end controls the compression mechanism, substantially as described.

17. In a bottle capping machine, the combination with a vertical shaft projecting above the cap plate of the machine, of a cam wheel mounted upon the upper end of said shaft, a rocking lever one end of which contacts with said cam wheel while the other end controls the compression mechanism, a gear wheel mounted upon the vertical shaft below the cap plate, a revolving chuck and a train of gearing for revolving said chuck from said shaft, substantially as described.

18. In a bottle capping machine, the combination with the standard and its cap plate and the vertical shaft, of a depending stud, a toothed sleeve arranged thereon, a revolving chuck and gearing connecting said sleeve with the vertical shaft and chuck, substantially as described.

19. The combination with the feed mechanism, of a stationary sleeve having a ball bearing, a movable sleeve arranged within the stationary sleeve, a centering rod extending through said sleeve, and a revolute chuck

- mounted upon said ball bearing, substantially as described.
20. In a bottle capping machine the combination with the cap feeding mechanism, of a depending stationary sleeve having a ball bearing at its lower end, a movable sleeve arranged within the stationary sleeve, and having a beveled lower end, a revoluble chuck mounted on said ball bearing and formed with channels, sliding blocks supported in said channels, one of said blocks having a cam surface while the other one carries a crimping roller, and a tilting lever adapted to contact with both of said blocks, substantially as described. 15
21. The combination with the revoluble chuck formed with an upper and a lower channel divided by a hollow partition, of a sliding block provided with a compression roller, a sliding block formed with a cam surface, a spring seated in the hollow partition and a tilting lever adapted to strike both of said blocks, substantially as described. 20
22. The combination with the stationary and movable sleeves extending into the chuck, of the centering rod, and sliding blocks seated in channels of the chuck one of said blocks having a cam surface adapted to contact with the beveled end of the movable sleeve, while the other block carries the compression roller, and a tilting lever adapted to strike said blocks, substantially as described. 25
23. The combination with a revolving chuck, of cam blocks, sliding blocks arranged in proximity to the cam blocks and a centrally fulcrumed striking lever, operated by the cam blocks the ends of which strike the sliding blocks, substantially as described. 30
24. The combination with the chuck, of a sliding block carrying the compression wheel at one end and provided with a plug at its op- 35
- posite end and a rocking lever carried by the chuck arranged to contact with the plug to press the sliding block inwardly, substantially as described. 45
25. The combination with the chuck, of a sliding block consisting of a headed rod section and a slotted tubular section; said rod fitting within the tubular section, a spring interposed between the sections, and a stop lug, substantially as described. 50
26. The combination with the chuck, of two sliding blocks seated in channels formed in the chuck, and means substantially as described for forcing one of said blocks outward and simultaneously forcing the other block inward, substantially as and for the purpose set forth. 55
27. The combination with the stationary and sliding sleeves, the latter formed with a beveled lower end, of a stationery centering rod, a lever for depressing said sliding sleeve, a revoluble chuck provided with channels, sliding blocks in said channels, and means for moving said blocks simultaneously in opposite directions, substantially as described. 60
28. In a bottle capping machine, the combination with a vertical shaft projecting above the cap-plate of the machine, of a cam wheel mounted upon the upper end of said shaft, a rocking lever one end of which contacts with said cam wheel while the other end controls the compression mechanism, a chuck, and means connected with the vertical shaft for revolving said chuck, substantially as de- 65
- scribed. 70
- In testimony whereof I affix my signature in presence of two witnesses.
- FRANK M. LEAVITT.
- Witnesses:
- G. MURRAY, Jr.
J. A. GRAY.

It is hereby certified that the name of the assignee in Letters Patent No. 527,209, granted October 9, 1894, upon the application of Frank M. Leavitt, of Brooklyn, New York, for an improvement in "Bottle-Capping Machines," was erroneously written and printed "The Bernadin Metallic Cork Company;" that said name should have been written and printed *The Bernadin Metallic Cork Company*; also on page 2, line 94, of the printed specification, the numeral "74" should read 47; same page, line 96, the numeral "47" should read 74, and page 3, line 1, the word "sleeves" should read *sleeve*; and that the said Letters Patent should be read with these corrections therein that the same may conform to the record of the case in the Patent Office.

Signed, countersigned, and sealed this 16th day of October, A. D. 1894.

[SEAL.]

JNO. M. REYNOLDS,
Assistant Secretary of the Interior.
